RIFFLER FOR CELLULOSE STOCK

William E. Henry, Hopewell, Va., assignor to
 Hercules Powder Company, Wilmington, Del.,
 a corporation of Delaware

Application August 7, 1943, Serial No. 497,789

4 Claims. (Cl. 92—28)

This invention relates to the refining of cellulose materials and more particularly to rifflers of the trough type which are used in conjunction with other processing equipment in the art of paper making.

Heretofore, a riffler in the form of a riffle trough, that is, a shallow wooden sluice equipped with a set of baffles all along the bottom and sometimes provided with a felt lining on the bottom, has been utilized to catch and retain the solid impurities in the paper stock. The riffler, generally, is on a level, without any incline, so that the current is leisurely, being produced by the pump that draws the stock from the riffler. In this trough the various heavy impurities that may be in the stock, such as particles of sand, metallic objects and the like, sink to the bottom and are held by the baffles or the felt or a combination of these. The capacity of the riffler should be sufficient to take care of the output of the digesters, or that portion of the digester output devoted to paper making and the length is governed chiefly by the amount of space able to be devoted to it, the longer the better.

The stock from the riffler is either pumped or gravitates to subsequent processing apparatus, such as diaphragm screens or other apparatus depending upon the particular process being employed. The riffler must be cleaned from time to time to remove the entrapped solid impurities. The prior art riffler devices are very difficult to clean and exceedingly expensive to maintain. This is particularly so when it is necessary to use felt to catch and retain the solid impurities, as the felt mats are expensive to replace. However, a felt mat on the bottom of the riffler still remains as the most effective means in the prior art devices to retain the solid impurities in the stock, particularly when it is necessary that the stock as discharged from the riffler be substantially free of solid impurities.

It is, therefore, the principal object of this invention to improve rifflers of this general type. Another object of this invention is to provide an improved riffle trough in which the solid impurities in the stock are more effectively removed, and the cleaning of the trough may be effectively and expeditiously performed. Other objects of the invention will appear hereinafter, the novel features and combinations being set forth in the appended claims.

Generally described, the present invention comprises a riffle assembly having in combination supported foraminous members with a plurality of settling areas disposed therebeneath and a

plurality of overflow sections disposed thereabove, said assembly being constructed in units and each unit adapted to be removed to facilitate and expedite cleaning of the settling areas.

5 A preferred embodiment of the invention has been chosen for purposes of illustration and description and is shown in the accompanying drawing forming a part of the specification wherein reference symbols refer to like parts wherever they occur: Fig. 1 is a fragmentary plan view of one form of apparatus for the embodiment of the invention; Fig. 2 is a fragmentary sectional view taken along the section 2—2 of Fig. 1; and Fig. 3 is a transverse sectional view of the apparatus shown in Fig. 1.

In Figs. 1, 2 and 3, a sluice 1 with sides 3 and 5 and a bottom 7 is provided with a liquid impervious metallic lining 9. A perforated screen 11, disposed along the bottom of sluice 1, has a plurality of supporting angle irons 13 rigidly secured to the bottom thereof. The screen 11 also has an angle iron 15 rigidly secured to the top thereof. A plurality of hinges 17 are rigidly secured through the screen 11 to the angle irons 13 and to the side 5 of the sluice 1. A longitudinal member 19 is rigidly secured to the screen 11 which member is in turn provided with a handle 21. The handle 21 in conjunction with the hinges 17 provides means for lifting the perforated screen 11 with its affixed members 13 and 15 and disposing the assembly to facilitate cleaning, as indicated by 23 in Fig. 3. A lock member 25 for each section of the screen 11 is pivotally secured to the side 3 of the sluice 1. This lock member serves to maintain the screen 11 firmly in position and the pivotal connection of the lock member 25 permits the disengagement of said member with the screen structure so that the screen structure may be placed in the position as indicated by 23. It is, of course, understood that a riffler is composed of a number of the above described units disposed in a sluice of considerable length, the length depending upon the particular processing problems involved, such as, the desired purity of the stock, the space available for the riffler, etc.

An example of the operation of the invention is given for removing solid impurities from paper stock. The stock is leisurely floated into the sluice 1, thereupon overflowing the members 15. This leisurely flow of the stock and the obstruction caused by the members 15 create in effect a stilling pool and the small solid impurities having a density greater than the stock migrate down through the perforated screen 11 and are en-

trapped within settling basins formed between the members 13. In this manner a highly efficient settling out of the solid impurities is obtained with the larger particles of the solid impurities being retained on the surface of the screen 11 and the finer particles entering the settling basin. The larger particles, being of considerable density, are not carried away by the stock overflow and the smaller particles which have migrated beneath the screen 11 are retained in the settling basin and are undisturbed by the overflow of stock thereabove. After a considerable period of use the large particles of solid impurities are removed by hand from the upper surface of the perforated screen 11, the screen is then raised to the position indicated by 23 in Fig. 3, and the small particles of solid impurities are flushed away with wash water or removed by other suitable means.

It is evident that there are numerous factors which will influence conditions for the most satisfactory operation of the invention, the actual limits of which cannot be established except by detailed study of each set of materials being processed and the intermediate and finished products involved. However, the riffler device of the present invention has been found highly effective in conjunction with the treatment of cellulose materials and more particularly cotton linters. In this particular adaptation of the invention the perforated screen consisted of $\frac{1}{8}$ -inch copper sheet perforated with $\frac{1}{8}$ -inch diameter holes on $\frac{7}{16}$ -inch centers. The angles were one inch brass angles and were welded to the perforated sheet. The perforated sheet was approximately three feet wide and eight feet long, the width conforming to the width of the sluice, and the length being such that the units could be easily lifted for cleaning purposes.

The advantages of the present invention reside in a riffler which provides a more efficient method of separating solid impurities from paper stock than has heretofore been attained and in addition provides a more expedient method for cleaning a riffler. This results in a minimum time of plant shutdown and an increase in overall plant production. A still further advantage resides in the economies of maintenance, as the efficiency of a riffler in accordance with the present invention is such that felt pads and like materials are unnecessary and the attendant high cleaning costs and replacement costs of these materials are eliminated.

What I claim and desire to protect by Letters Patent is:

1. A riffler for use in treating a stock of cellulose materials having in combination a sluice trough and a plurality of rifle units disposed therein; the sluice trough having water impervious sides and bottom members; and each of the rifle units comprising a substantially plane foraminous screen member provided with a multiplicity of perforations in spaced relationship to the bottom of said trough; a plurality of supporting and spacing members securely affixed to the bottom of the foraminous member transversely of the trough adapted to maintain said spaced relationship and provide stilling areas between said supporting members; at least one overflow member of substantial height disposed above said

foraminous member; and means for integrally removing said unit from its functioning position to a second position whereby cleaning of the sluice trough is facilitated.

5 2. A riffler for use in treating a stock of cellulose materials having in combination a sluice trough and a plurality of rifle units disposed therein; the sluice trough having water impervious sides and bottom members; and each of 10 the rifle units comprising a substantially plane foraminous screen member provided with a multiplicity of perforations in spaced relationship to the bottom of said trough; a plurality of supporting and spacing members securely affixed to the bottom of the foraminous member transversely of the trough adapted to maintain said spaced relationship and provide at least one stilling area between said supporting members; at least one overflow member of substantial height affixed to the top of the foraminous member adapted to provide an overflow section transversely of the trough; and means for removing said unit from its functioning position to a second position whereby cleaning of the sluice trough is facilitated.

20 3. A riffler for use in treating a stock of cellulose materials having in combination a sluice trough and a plurality of rifle units disposed therein; the sluice trough having water impervious sides and bottom members; and each of 30 the rifle units comprising a substantially plane foraminous screen member provided with a multiplicity of perforations in spaced relationship to the bottom of said trough; said foraminous member being hingedly secured to a side of the said trough and adapted to be lifted from its position in spaced relationship to the bottom of the trough to a second position in juxtaposition to the side of said trough; a plurality of supporting and spacing members securely affixed to the bottom of the foraminous member transversely of the trough adapted to maintain said spaced relationship and provide at least one stilling area between said supporting members; and at least 35 one overflow member of substantial height affixed to the top of the foraminous member adapted to provide an overflow section transversely of the trough.

40 4. A riffler for use in treating a stock of cellulose materials having in combination a sluice trough and a plurality of rifle units disposed therein; the sluice trough having water impervious sides and bottom members; and each of 45 the rifle units comprising a substantially plane foraminous screen member provided with a multiplicity of perforations in spaced relationship to the bottom of said trough; a plurality of supporting and spacing members of substantial height securely affixed to the bottom of the foraminous member transversely of the trough and in lower-edge proximity thereto and providing stilling areas between adjacent pairs of said supporting members; at least one overflow member of substantial height affixed to and disposed above the foraminous member transversely of the trough; and means for integrally removing said unit from its functioning position to a second position whereby cleaning of the sluice trough is facilitated.

70 WILLIAM E. HENRY.
